CLAIM

The ornamental design for a sprayer of cosmetics, as shown and described.

DESCRIPTION

FIG. 1 is a front elevational view of a sprayer of cosmetics, showing my new design;

FIG. 2 is a side elevational view thereof from the left of FIG. 1, the side elevational view from the right of FIG. 1 being the mirror image thereof;

FIG. 3 is a rear elevational view thereof;

FIG. 4 is a bottom plan view thereof; and,

FIG. 5 is a top plan view thereof.
